CELL DOOR OPERATING AND LOCKING SYSTEM

Frederick A. Montgomery, Cleveland, James T. Van Dorn, Rocky River, and Harry D. Garber, Cuyahoga Falls, Ohio, assignors to The Van Dorn Iron Works Company, Cleveland, Ohio, a corporation of Ohio

Application February 21, 1941, Serial No. 380,038

12 Claims. (Cl. 189—7)

This invention relates to door locking and operating mechanism for jails and other institutions and, among other objects, aims to provide a greatly improved system wherein a plurality or series or gang of sliding cell doors are arranged to be operated, to either or both unlocked and open and closed and locked relation either individually and manually or collectively by a single actuating means. The main object is to provide improved auxiliary locking means both for locking the cell doors in their closed position and their opened position, said auxiliary locks coacting with the respective door hangers. Another object is to provide a novel combination of auxiliary locks and combination spring bumper and door starters so constructed and arranged that when the doors are unlocked by the usual locking members, the bumpers will hold the locking members in their unlocked positions and the parts will remain in such position until the doors are again closed, when the auxiliary locks will be automatically tripped and the doors will be again locked. Still another purpose is to provide in a system of this type novel latch members which serve to connect the door hangers to a pull bar. A still further object is to provide resiliently mounted latch bolts on the door hangers to permit any jammed door to be disengaged from the operating mechanism, said resilient mounting permitting pull bar actuation of all the doors fully to close them even when the pull bar has expanded or contracted or the parts have become worn. A still further object is to provide novel means simultaneously to disconnect any latch bolts from the pull bar and lock the associated door carriage in open position. Also, an important object is to provide for over-travel of the doors when they are opened by pull bar actuation to permit them to kick back slightly toward closed position and there be locked open and, at the same time, be free for manual and individual closing. Another important object is to provide a jail system wherein the locking and operating mechanism over the doors is mounted entirely on the bottom and rear walls of the track box, so that the front and top walls of the track box may be removed as a unit, thereby providing greater accessibility to the mechanism.

This application embodies certain improvements over a copending application Ser. No. 366,478, filed November 20, 1940.

With the above and other objects in view, some of which will be apparent to those skilled in the art and others of which are inherent in the construction and association and use of the

parts, this invention includes certain novel features of construction and combinations and arrangements of parts, which will be hereinafter set forth in connection with the accompanying drawings, wherein:

Fig. 1 is a fragmentary view, partly in elevation and partly in section, showing one embodiment of this invention applied to a single sliding door with the door in closed and locked position;

Fig. 2 is a fragmentary view similar to Fig. 1 on an enlarged scale showing the door unlocked and partially opened;

Fig. 3 is a similar view showing the door locked in opened position;

Fig. 4 is a horizontal sectional view taken on the line 4—4 of Fig. 1;

Fig. 5 is an enlarged fragmentary elevational view, partly in section, showing details of the mechanism for locking the door opened;

Fig. 6 is a transverse sectional view taken on the line 6—6 of Fig. 5;

Fig. 7 is a view similar to Fig. 5 showing the parts in another position;

Fig. 8 is a transverse sectional view taken on the line 8—8 of Fig. 7;

Fig. 9 is an enlarged fragmentary elevational view similar to Fig. 5 showing details of the mechanism for locking the door closed;

Fig. 10 is a transverse sectional view taken on the line 10—10 of Fig. 9;

Fig. 11 is a fragmentary detail view showing parts as illustrated in Fig. 9 in another position; and

Fig. 12 is a transverse sectional view taken on the line 12—12 of Fig. 11.

The adaptation of the present invention illustrated in the drawings is suitable for embodiment in a system and for use with a longitudinal row of cells each having a sliding door 20, only one such door and means for actuating it being here shown for convenience of illustration. This door can be mounted in the same manner as is disclosed for example in said copending application and also in the patent to Garber 1,908,234, having a hanger 21 carried by rollers 22 in a track box 23 above the row of doors. The rollers are guided on a track 24 shown as being secured to the back wall of the track box. In this instance, the doors are adapted to be operated either manually or selectively and collectively by means of a pull rod 25 extending substantially the full length of the track box and connected at one end to a screw extension 26 adapted to be operated by a screw threaded sleeve or nut mem-

ber 27 which projects into a cover box or housing 28 at the end of the group of cells. The sleeve is shown as being journaled in a bearing 29 at the back of the cover box 28 and it is operated by a sprocket chain 30 connected through gears 31 and 32 to a hand crank 33 in much the same manner as is disclosed in the aforesaid co-pending application.

Each hanger 21 is shown as carrying a resiliently mounted latch bolt 34 slidably mounted in a U-shaped guide bracket 35 which, in turn, is pivoted at 36 to the hanger, the upper end of the guide bracket having an expansion coil spring 37 connected normally to hold it in its vertical or upright position with the lower left hand edge, viewed in Figs. 5 and 7, engaging the pin 38. The latch bolt is adapted to engage an ordinary gap nut 39 on the pull bar 25 having a notch or gap 40 between upstanding cam projections 41 and 42, the forward projection 41 being lower than the rear projection 42. The lower end of the latch bolt 34 carries a rearwardly projecting trunnion 43 on which is journaled a roller 44. The roller rides on a latch bolt bar 45 shaped at its forward end to provide a lifting cam surface 46 designed to raise the latch bolt to an intermediate position when the door is locked, as shown in Fig. 1, so that the gap nut may be free to move to the left. The ends of the latch bolt bar 45 are pivoted to crank arms 47 and 48, the forward arm 47 being a part of the bell crank 49 having a pin and slot connection to a pull rod 50 connected to be actuated when a selector knife blade or lever 51 pivoted at 52 in the housing 28 is operated to unlock the door as will be hereinafter explained. Herein, the knife blade 51 carries a flexible pull element 53 trained over sheaves 54 and connected by a rod 55 to one arm of a bell crank lever 56. The other arm is connected through a link 57 to one arm 58 of a U-shaped lever 59, the other arm 60 of which has a pin and slot connection 61 to a vertically movable locking bar 62.

The bell crank 56 and lever 59, as perhaps best illustrated in Figs. 9, 10 and 11, are shown as being pivoted on a vertical metal bar 63 secured by means of brackets 64 and 65 to the back wall of the track box and extending downwardly through a pilaster 66. The pull elements 53 leading from the housing 28 to the successive bell cranks 56 for the different doors are arranged at different heights in vertical formation behind the bars 63. For this purpose, each bar 63 is provided with a series of openings or perforations 67 to receive the pivot bolts or pins 68 of the respective bell cranks 56. The arms 58 and 60 of the lever 59 are mounted on opposite sides of the bar 63, being secured on a shaft 69 journaled in the bar 63 and in a vertical bracket 70 spaced from the bar 63 but secured thereto at its opposite ends. The arm 58 is in vertical alignment with the bell crank 56 and the arm 60 is between the bar 63 and bracket 70. It will be understood that each lever 59, one for each door, is arranged in a pilaster below the track box at the same height as that shown in Fig. 9. Thus, in any installation, regardless of the number of cells, the mechanism will be substantially standardized except for the length of the links 57 connecting the bell cranks 56 and the levers 59. It will be noted that the bell crank 56 is arranged substantially centrally between the bar 63 and the back wall of the track box, the idea being to mount the bell cranks for two successive doors at the same elevation. Then the pull element 53 for

one of such doors can be connected to the rear face of one bell crank, while the pull element 53a for the next bell crank may pass in front of the first bell crank, as indicated in Figs. 9 and 10.

5 The bell crank 56 is shown as being mounted in the top openings 67, but it is to be understood that the bell cranks for the first two doors nearest the control housing 28 will be mounted in the lowermost or number 1 openings 67 of the bars 63, the next two bell cranks in the next higher or number 2 openings, and so on. Thus for the fifteen openings 67 indicated in bar 63 there could be a cell block containing thirty doors.

10 The locking bar 62 is shown as extending downwardly through the pilaster 66 and carries the usual spring-urged bolt 71 at its lower end coacting with a notched tongue 72 on the door 20. To prevent any of the mechanism in the 15 track box from being released should a prisoner in some manner raise the bolt 71, the locking bar 62 is shown as being made in sections, the upper section 73 being formed of two sections of strap metal secured together and bent to form a clevis mounted for vertical sliding movement in guides 20 secured to the bracket 70 and a wall of the pilaster 66 respectively. A block 74 is secured between the lower side portions of the clevis and the lever arm 60 extends between and has its 25 pin and slot connection 61 to the side portions above the block. The other section of the locking bar 62 is shown as comprising a rod 75 slidably mounted in the block 74 and carrying a nut at its upper end normally resting on the 30 top of the block 74. The lower end of the rod is connected to the bolt 71. Thus, when the clevis is raised, the bolt 71 will be raised but should the bolt be raised the clevis will remain stationary.

35 When the locking bar 62 is raised it also actuates an auxiliary hanger lock in the form of a pivoted hook 76 having a bill 77 adapted to engage a laterally extending pin 78 on the hanger, as best disclosed in Figs. 1 and 9 in which the door is shown as being locked closed. The clevis portion 73 of the locking bar 62 has upper and lower laterally extending fingers or plates 79 and 80, straddling the hook 76. When the parts are in their normal locked closed position, the upper fingers 79 rests on the upper edge 81 of the hook and the lower finger 80 is spaced beneath the lower edge of the hook which is cut away to provide a curved shoulder 82 in vertical alignment with the finger 80. When the locking bar 62 is raised, the finger 80 will engage the shoulder 82 and the hook will also be raised or swung up. The hook 76 is shown as having a forwardly offset ear 83 adjacent to the upper edge 81 to which is pivotally connected the forward end of the pull rod 50. The upper edge of the hook is shown as having an upstanding locking shoulder 84 with a vertical face adjacent to the finger 79 so that it will bind or strike against the rear face of the finger 79 if any attempt is made to raise the hook without operating the locking bolt 62 when the door is locked closed, as will be apparent from the position of the parts in Fig. 9. When the locking bar is raised slightly, the shoulder 84 is free to swing clockwise to permit the hook to be disengaged from the pin 78 on the hanger 21.

40 The arrangement of the parts thus far described is such that when the knife blade lever 51 is pulled downwardly it will impart clockwise movement to the bell crank 56 to raise the locking bar 62 and consequently the bolt 71 to

unlock it from the tongue 72. At the same time, the finger 79 is clear of the shoulder and continued upward movement of the locking bar 62 will cause the finger 80 to raise the hook 76 and disengage it from the pin 78, at which time the rear pin 85 of the rod 50 will be in the forward end of the slot in the bell crank 49. Further upward movement of the bar 62 will raise the latch bolt bar 45 and thus lift the latch bolt 34 clear of the notch 40 in the gap nut 39. When this happens, the knife blade has been pulled down as far as possible and the door is free to be opened.

In this example, each door is adapted to be initially kicked open by a pivoted spring bumper or starter 86 having a finger 87 engaging the front of the pin 78 when the door is locked closed. Starter 86 is pivoted to be swung counter-clockwise by a coil spring 88 (Figs. 9 and 12) and is stopped in substantially a vertical position as shown in Fig. 11 by a toe 89 which is shown as engaging the bottom of the track box. When the bumper or starter reaches this position, the upper end of its finger 87 lies directly in the downward swinging path of the bill 77 on the hook 76. The attendant or operator then releases the knife blade lever 51 and the spring of the locking bolt 71 pulls the locking bar 62 to the position shown in Fig. 2 with the bill 77 of the hook supported on the finger 87 of the bumper, as shown in Figs. 2 and 11. In this position, the finger 79 rests on the upper edge of the shoulder 84 on the hook and holds the locking bolt in raised position shown in Figs. 2 and 11. Also, the knife blade lever is automatically moved to the intermediate position shown in dotted lines in Fig. 1 so that the lever indicates the unlocked and partially opened condition of the corresponding door.

All of the foregoing operations take place while the gap nut is in the position shown in Figs. 1 and 2. It will be noted that, when the knife blade or lever 51 was released, the latch bolt bar 45 was also lowered to its lowest position by virtue of the pin and slot connection of the bell crank arm 49. As the door was kicked open, the latch bolt 34 moved beyond or to the left of the notch in the gap nut and the roller 44 on the latch bolt rolled down and beyond the cam surface 46 of the latch bolt bar. The latch bolt thus has dropped approximately to the level of the bottom of the notch 40 and, if the doors are to be mechanically opened, the bottom of the bolt may ride up on the upper face of the cam projection 42 and drop into the notch again when the gap nut is moved to the left. Thus, all gap nuts may be actuated to pick up all kicked open doors to carry them to their fully opened position or return them to closed position. It is only necessary to turn the crank 33 to move the pull bar to the left so that all of the freed latch bolts will fall into the corresponding or correlated gap nut notches.

Assuming that all of the unlocked doors are mechanically opened, continued movement of the the pull rod 25 to the left will move the doors slightly beyond their locked open position as best shown in Fig. 7. Each door hanger strikes a rear spring bumper or door starter 90, moving the starter to a position to exert force to kick the door toward closed position. The latch bolt 34 remains in the notch 40 of the gap nut. If it is desired to leave all selected opened doors in this position without operating other doors mechanically, the latch bolts and the gap nuts can

remain in this engaged position and serve as locks for the doors. However, it is desirable to release the latch bolts from the gap nuts so that selected doors may be either opened or closed mechanically. To that end, each hanger has a gravity locking bolt 91 which cooperates with separate locking means in the track box. This locking means is shown as including a locking plate 92 pivotally mounted at its rear end of the back face of an angle bracket 93 secured to the bottom of the track box near the rear edge of open door. Incidentally, the rear spring bumper 90 is also mounted on the bracket 93. The plate 92 has a notch 94 in its upper edge and this edge is curved downwardly on either side of the notch to provide cam portions 95 and 96. Incidentally, the front edge of the notch is higher than the rear edge. The plate 92 is mounted in vertical alignment with the rear crank arm 48 of the latch bolt bar 45 and the pivot 97 of the plate is to the rear of the arm 48. The lower edge of the plate 92 is cut away to provide a cam surface 98 which is engaged by the curved upper, rear edge of the crank arm to cause the plate to be swung counterclockwise when the latch bolt bar is raised. The lower forward end of the arm 48 is carried by a stub shaft 99 journaled in a bracket 100, and this shaft also carries a supporting arm 101 having its forward upper edge cam shaped to engage a lateral pin 102 at the front end of the plate 92 as it reaches its raised position and hold the rear upper edge of the plate against a lateral stop pin 103 rigidly to hold the plate in locked position. As the plate is raised, its rear cam portion 95 strikes the lower edge of the gravity bolt 91 and partially raises it. It will be noted that the bolt 91 is slidably mounted for vertical movement only in a guide 104 on the carriage 21 and has upper and lower stop shoulders 105 and 106. It is normally suspended with the upper shoulder 105 resting on the top of the guide 104.

As soon as the doors have reached the overtraveled position corresponding with that shown in Fig. 5, the knife blade levers 51 are lowered to raise the latch bolts to their uppermost positions, free from the notches in the gap nuts and, at the same time, to operate the mechanism to lock the door open as best shown in Figs. 3 and 7. When the latch bolts reach an intermediate raised position to clear the projections 41 of the gap nuts, the door hangers are free to be kicked toward closed position by the starter 90. Continued lifting movement of the latch bolt bar will cause the locking plate 92 to be raised to its locking position shown in Fig. 7. As the door is also being kicked toward closed position, the lock 91 strikes the forward edge of the notch 94 and arrests the door movement, at the same time the bolt drops downwardly until the shoulder 105 strikes the top of the guide 104, the parts assuming the final position shown in Fig. 3. Thus, each opened door is kicked to the right to its locked open position and the starters still remain slightly tensioned or sprung to kick the doors toward closed position when they are again unlocked.

To hold the locking plates 92 in their uppermost or raised positions, as shown in Figs. 3 and 7, it is necessary to hold down or lock the knife blade levers in their lowermost positions, as shown in dotted lines in Fig. 1. Any suitable latch means in the control housing, such as ordinary latch hooks (not shown), can be used for this purpose. These latch hooks, disposed in-

side of the housing, may be operated by buttons 107 to engage and latch upon the upper edges of the levers and to be disengaged or unlatched therefrom.

When all open doors are locked open and the latch bolts are free of the gap nuts, the gap nuts and associated parts may be used to pick up and open other doors or the gap nuts may remain in their inactive position shown in Fig. 3. In this position, it will be noted that the latch bolt 34 has been moved forwardly out of alignment with the gap nut notch 40, so that when the latch bolt bar 45 is lowered to unlock the door, the bottom of the latch bolt will strike the top of the cam projection 41 and ride down its forward surface as the door is pushed forward by the bumper 90.

If a selected door is to be opened manually, the associated knife blade is pulled down to unlock the closed door and permit it to be kicked initially toward open position, as has already been explained. Instead of releasing the knife blade, it is locked down by operating the button 107, thus holding the locking plate 92 elevated in the position shown in Figs. 3 and 7. The door is then manually pushed toward open position and, as it approaches fully open position, the lower edge of the bolt 91 rides up the cam portion 96 and drops into the notch, thus locking the door open. At the same time, the carriage 21 causes the bumper 90 to swing counterclockwise and places its spring under tension to kick the door toward closed position.

To release the latch bolts and thus unlock the locked-open doors, it is only necessary to release the respective knife blades thus permitting the springs of the lock-bolts 71 to pull down the lock bars 62 and thereby lower the latch bolt bars 45. This permits the locking plates 92 to swing clockwise so that the forward edge of the notch 94 clears the lower edge of the bolt. At the same time, the latch bolts fall until they strike the cam portions 41, if the gap nuts are in their extreme rear positions, and the spring bumpers 99 will kick the doors toward closed position, as has just been explained. When this happens, the released door can be closed either manually or mechanically. When the doors reach their closed position, the spring bumpers 86 are tripped or sprung to the right by the pins 78 and the bills of the hooks 76 will drop into locking engagement with the pins. At the same time, the locking bars 62 are released so that the locking bolts 71 engage the notched tongues 72 of the doors and the knife blades are automatically raised to their uppermost positions, as indicated by full lines in Fig. 1. This position of the knife blades indicates that the respective doors are locked closed.

If the doors are to be closed mechanically after they are initially kicked or started toward their closed positions, it is only necessary to operate the crank 33 to move the pull bar to the right, if the gap nuts have been left in their extreme gear position or, to the left if they have been returned to their forward position, and bring the gap nuts into registry with the latch bolts, which latch bolts through camming force on their lever ends, will rise over the cam projections 41 or 42 as the case may be, and fall into the notches 40. When all of the doors are thus picked up by their respective gap nuts, the pull bar is operated to close and lock the doors, as previously described.

As all of the mechanism is mounted on the

back wall or bottom of the track box, the front and top wall of the track box may be removed as a unit to provide greater accessibility to the mechanism. Referring to Fig. 10, the front vertical wall 108 is made integral with an inclined top wall 109, said top wall being bent downwardly at its back edge to provide a flange 110 adapted to hook over the top edge of the back wall 111. The front edge of the bottom wall is bent upwardly to form a flange 112 and the lower portion of the front wall carries a plate 113 spaced therefrom adapted to engage behind the flange 112 while the front wall abuts the front face of the flange. To remove the cover 108-109 it is only necessary to raise it vertically. To hold the cover assembled on the track box, the walls 108 and 109 are shown as having vertical reinforcing ribs connecting them, one such rib 114 being shown in Fig. 10 and indicated in dotted lines in Fig. 9. Each rib has a horizontal shoulder 115 near its rear upper edge over which is adapted to be projected a locking lug 116 carried by a rod 117 slidably mounted in brackets 118. The lug 116 has a vertical rear face abutting the rear wall 110 so that it is guided to move horizontally. The rod 117 extends into the track control cabinet 28 as shown in Fig. 1, from which it can be reciprocated in any convenient manner. Thus, the cover 108-109 cannot be removed until the rod is moved to release the lugs from their engagement with the shoulders 115. Then the cover may be lifted and removed to expose the mechanism in the track box.

From the foregoing, it will be seen that we have provided door locking and operating mechanism particularly suitable and adaptable for use in jails, prisons, asylums and other institutional installations, which mechanism is simple in its construction and dependable in operation; and that all of the doors or selected doors can be operated either manually or mechanically. Moreover, each door is automatically locked in closed position and the auxiliary locks for the carriage cannot be unlocked until the knife blades are operated by the keeper. The springs for the main locks also operate the knife blades so that they indicate that the doors are locked closed. When the doors are actuated mechanically the operating mechanism serves to prevent them from being actuated by the prisoners. If any door becomes jammed, it is automatically released from the gap nut to permit the rest of the doors to be closed. The mechanism is standardized for locking systems embodying any number of doors up to the maximum.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. In operating and locking mechanism for jails and the like having a plurality of sliding doors, a main locking member and an auxiliary lock connected to lock each door in closed position; lock operating means connected to actuate both locks, said auxiliary lock coacting directly with the door carriage and the main locking member; a separate gravity latch carried by the door; a movable locking member coacting with said latch to lock the door open; and a single actuating member connected to operate

the main lock, the auxiliary lock and the movable locking member.

2. In a master operating and locking system for jails and other installations having a plurality of sliding doors, a track box; hangers for the doors in the track box; a main vertical locking bar for each door; an auxiliary hook shaped locking member coacting with the hanger of each door and connected to be operated simultaneously with the locking bar; a plunger latch member carried by each door hanger; a gravity operated latch carried by each door hanger; a pivoted locking plate mounted in the bottom of the track box and coacting with the gravity latch to lock the door open; a lever connected to operate the locking bar, the locking plate and plunger for each door; a pull bar carrying a series of gap nuts, one for each door, adapted to be engaged by the respective plunger latches; and means on the plunger latches to hold them out of engagement with the respective gap nuts so that the pull bar is free to operate other doors.

3. In a jail door locking system of the class described having sliding cell doors and a track box above the doors, a main lock and an auxiliary lock for locking each door closed; a lock operating lever connected to release said main and auxiliary locks simultaneously; a latch bolt bar in the bottom portion of the track box also connected to be operated by said lever; a pivoted locking member in the track box for locking the door open connected to be actuated by said latch bolt bar; and a latch member carried by the door to engage said locking member.

4. In a jail door locking system of the class described having sliding cell doors and a track box above the doors, a main lock and an auxiliary lock for locking each door closed; a door carriage in the track box; a lock operating lever connected to release said main and auxiliary locks simultaneously; a latch bolt bar in the bottom portion of the track box also connected to be operated by said lever; a pivoted locking member in the track box for locking the door open connected to be actuated by said latch bolt bar; and a gravity operated plunger latch mounted on the door carriage coacting with said pivoted locking member.

5. In a jail door locking system of the class described having sliding cell doors and a track box above the doors, a main lock and an auxiliary lock for locking each door closed; a lock operating lever connected to release said main and auxiliary locks simultaneously; a latch bolt bar in the bottom portion of the track box also connected to be operated by said lever; a pivoted locking member in the track box for locking the door open connected to be actuated by said latch bolt bar; a gravity locking bolt carried by the door coacting with said pivoted locking member; a pull bar having a gap nut; and a coupling member on the door, also actuated by said latch bolt bar to connect the door to be opened or closed by said pull bar.

6. In a jail door locking system of the class described having sliding cell doors and a track box above the doors, a main lock and an auxiliary lock for locking each door closed; a lock operating lever connected to release said main and auxiliary locks simultaneously; a latch bolt bar in the bottom portion of the track box also connected to be operated by said lever; a pivoted locking member in the track box for locking the door open connected to be actuated by said latch bolt bar; a gravity locking bolt carried by the

door coacting with said pivoted locking member; a pull bar having a gap nut; a coupling member on the door, also actuated by said latch bolt bar to connect the door to be opened or closed by said pull bar; and a removable front cover plate for the track box extending upwardly and then rearwardly from the bottom wall to the back wall of the track box to expose all of the operating parts therein for adjustment and repairs.

7. In combination with a sliding door, a main vertical locking bar for said door; an auxiliary hook-shaped locking member co-acting with the carriage of said door; means connecting said main locking bar and said auxiliary locking member to be manually actuated simultaneously, including a loose connection whereby the locking bar can be forced to released position without releasing the auxiliary locking member; and a spring urged member engageable with said auxiliary locking member when unlocked to hold both the auxiliary locking member and the main vertical locking bar in their unlocked positions until the door is reclosed.

8. In combination with a sliding door and a track box above said door and in which the door is slidably mounted, a hollow pilaster at the closing side of the door; a main vertical locking bar carried in said pilaster; an auxiliary hook-shaped pivoted locking member in said track box engageable with a portion movable with the door for locking said door in closed position; means connecting said main locking bar and said auxiliary locking member to be manually actuated simultaneously including a loose connection whereby the locking bar can be forced to released position without releasing the auxiliary locking member; and a spring urged pivoted door starter connected to hold the auxiliary locking member and the main vertical locking bar in their unlocked positions until the door is reclosed.

9. In a master operating and locking mechanism for jails and other installations having a plurality of sliding doors, a latch bolt carried by each door; a main lock and an auxiliary lock to lock each door in closed position; means including a separate gravity latch carried by the door and a pivoted locking member coacting therewith for locking each door in normal open position; a spring urged starter coacting with the hanger of each door and biased to move the door toward closed position; a single member for operating all of the locks for each door; and a pull bar having gap nuts adapted to be engaged with the latch bolts mechanically to open and close the doors, said mechanism constructed to permit over-travel of the door beyond its normal open position by its gap nut whereby the door will be returned automatically to its normal locked open position by the spring starter with the gravity latch and the pivoted locking member engaged when the latch bolt and its gap nut are disengaged.

10. In combination with a sliding door; a mechanism including mechanically operated door opening and closing means; latch means by which said door is connected to and disconnected from said operating means; a separate gravity latch carried by the door; a swingable locking plate engageable by said separate gravity latch when the door is in normal open position to lock the door in said position, said mechanism constructed to permit over-travel of the door beyond its normal open position by the operating means; and means connected automatically to

return the door from said over-travel position to said normal locked open position with the swingable locking plate engaged by the gravity latch after said latch means is disconnected from said operating means.

11. In combination with a sliding door, a mechanism including mechanically operated door opening and closing means, latch means by which said door is connected to and disconnected from said operating means; a separate gravity latch carried by the door; a swingable locking plate engageable by said separate gravity latch when the door is in normal open position to lock the door in said position; a lever connected to disconnect the latch means from the door operating means and simultaneously move said locking plate to its locking position, said mechanism constructed to permit over-travel of the door beyond its normal open position by the operating means; and means connected automatically to return the door from said over-travel position to said normal locked open position with the swingable locking plate engaged by the gravity latch after said latch means is disconnected from said operating means.

12. In combination with a sliding door, a mechanism including mechanically operated door opening and closing means; latch means by which said door is connected to and disconnected from said operating means; a locking member carried by the door and separate from said latch means; a pivoted member engageable by said locking member when the door is in normal open position; manually operable means to actuate said latch means to the connected and disconnected position; means also connecting said manually operable means to actuate said pivoted member, said mechanism constructed to permit over-travel of the door beyond its normal open position by the operating means; and means connected automatically to return the door from said over-travel position to said normal locked open position with the pivoted member engaged by the locking member after said latch means is disconnected from said operating means.
